UNITED STATES PATENT OFFICE

2,463,270

PEG PUZZLE PIECES AND PLAYBOARD

Joseph M. Hirsch, New York, N. Y.

Application April 11, 1945, Serial No. 587,646

2 Claims. (Cl. 273—157)

1

This invention relates to new and useful improvements in an educational peg toy game.

More specifically, the invention proposes the construction of an educational peg toy game characterized by a playboard upon which puzzle pieces are adapted to be placed together and which is provided at its top with a small picture of the puzzle to be assembled as a guide to assembling the puzzle.

Still further the invention proposes providing a plurality of apertures across the face of the playboard and to provide each of the puzzle pieces with pegs adapted to be inserted into one of the apertures for retaining the piece in a fixed position.

Still another object of the invention, proposes the construction of a puzzle which may be interrupted at any point during its assembly, and which may be laid aside for an indefinite period without the danger of the pieces being jumbled.

Still another object of the invention proposes the provision of a means for adjustably mounting the pegs on the back of the puzzle pieces so that they may be adjusted thereon to suit the requirements of the location of a hole on the playboard permitting the peg of the piece to be engaged with the hole in a proper position of the piece with respect to other pieces of the puzzle.

It is a further object of the invention to construct an educational peg toy game, as briefly stated, which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an educational peg toy game constructed in accordance with this invention.

Fig. 2 is a longitudinal vertical sectional view taken on the line 2—2 of Fig. 1.

Fig. 3 is a fragmentary enlarged transverse sectional view taken on the line 3—3 of Fig. 1.

Fig. 4 is a bottom perspective view of one of the pieces shown in Fig. 1.

Fig. 5 is a vertical sectional view of the piece shown in Fig. 4.

Fig. 6 is a bottom view of a piece for use in the educational peg toy, but constructed in accordance with a modified form of this invention.

2

Fig. 7 is a sectional view taken on the line 7—7 of Fig. 6.

The educational peg toy game, in accordance with this invention includes a playboard 10 having a plurality of apertures 11 across its face. A puzzle is adapted to be assembled on the board over the apertures 11. A picture 12 of the puzzle to be assembled upon the board is printed in position above the apertures. This picture 12 is to act as a guide in assembling the puzzle pieces upon the board.

The puzzle has a plurality of puzzle pieces 13 which are provided for being assembled upon the board 10. Each of the pieces 14 is provided with a small downwardly projecting peg 14 which is adapted to be inserted into one of the apertures 11 for retaining the particular piece in a fixed position, upon the board. Each of the pieces 13 is constructed of super-imposed layers of material 15 which are fixedly secured together by the application of mucilage between the adjacent faces thereof. Each of the pegs 14 has a head 17 secured in position between the layers 15 for securing the peg fixedly in position.

Providing the puzzle pieces 13 with pegs 14, upon the bottom faces for insertion into the aperture 11 upon the playboard, permits the pieces 13 to be retained in position upon the board 10 and permits the assembling of the puzzle to be interrupted at any time prior to its completion so that the incompletely assembled puzzle may be laid aside without the danger of the pieces becoming jumbled.

The board 10 is constructed of a plurality of layers 20, or laminations which are pasted or cemented together. At the top, the board 10 is formed with a cutout, or cavity 21 which is in the nature of a pocket for storing the pieces used in the educational peg toy game. This pocket 21 is divided into several sections with partitions 22 so that different pieces may be stored in the different pockets. It is proposed that several groups of pieces 13 be provided, which distinguish from each other, in color. They may also distinguish from each other in shapes. Four, or five different designs may be provided to give the game sufficient interest. The picture 12 may be of an animal, a figure, or transportation devices, such as a plane, ship, or a train. The board 10 with the apertures 13 very closely resembles a punch board.

In the modification of the invention disclosed in Figs. 6 and 7 a means is provided for adjustably mounting the pegs 14 in position upon the bottom faces of the puzzle pieces 13 so that they may be adjusted to be engageable with a se-

lected one of the apertures 11 of the playboard. To accomplish this, the bottom layer 15' of the pair of superimposed layers 15' forming the puzzle piece 13' is formed with a slot 18 having a plurality of branches 19 into which the peg 14 is adapted to be selectively engaged to retain the peg 14 in one of many possible adjusted positions on the bottom face of the piece 13'.

The slot 18 has its edges formed with an under cut, or grooves 22, for accommodating the head 17 of the peg 14. This under cut, or groove 22 guides the head 17 of the peg while it is moved to different positions along the slot 18. It also supports the peg 14 so that the shank portion of the peg, extends at right angles to the body of the piece 13'.

In other respects this form of the invention is identical to the prior form and like parts may be recognized by the same reference numerals.

It is to be understood that the picture 12 may be that of an animal, object or a combination of a number of figures of any type, so that the child may follow any one of the patterns which may be either distinct patterns or superimposed.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A peg toy game comprising a playboard having a plurality of holes formed therein, a plurality of pegs selectively engageable with said holes, and puzzle pieces movably mounted on said pegs for adjustably positioning said puzzle pieces relative to each other and to the playboard.

2. A peg toy game comprising a playboard having a plurality of holes formed therein and a plurality of puzzle pieces adjustably positionable on said playboard and provided with pegs for selectively engaging said holes, each puzzle piece comprising a laminated member having a branched slot formed therein to accommodate its peg in movable relation thereto, said peg having a head formed thereon and said slot being enlarged interiorly of said puzzle piece to accommodate the head of said peg, thereby holding said peg and said puzzle piece together.
